UNITED STATES PATENT OFFICE.

DAVID CHEW, OF PHILADELPHIA, PENNSYLVANIA, ASSIGNOR OF ONE-HALF TO ELTON G. IDELL, OF PHILADELPHIA, PENNSYLVANIA.

CAR-FENDER.

1,087,276.

Specification of Letters Patent. Patented Feb. 17, 1914.

Application filed May 14, 1913. Serial No. 767,515.

To all whom it may concern:

Be it known that I, DAVID CHEW, a citizen of the United States, residing at Philadelphia, in the county of Philadelphia and 5 State of Pennsylvania, have invented certain new and useful Improvements in Car-Fenders, of which the following is a specification.

My invention relates to improvements in 10 car fenders, the object of the invention being to provide an improved construction of scoop or pick up fender normally elevated and forced downwardly by the action of a tripping fender which is engaged by a person or object on the track.

A further object is to provide improved 15 means for holding the pick up fender in its lowered operative position, when the tripping fender is moved to its rearward elevated position.

A further object is to provide a fender 20 with an improved scoop or pick up member and improved laterally movable arms connected to the scoop and to a frame in rear of the scoop supporting the same, so 25 that a netting receptacle is formed to hold a person or object picked up by the scoop member.

With these and other objects in view, the 30 invention consists in certain novel features of construction and combinations and arrangements of parts as will be more fully hereinafter described and pointed out in the claims.

35 In the accompanying drawings: Figure 1 is a view in side elevation illustrating my improved fender in normal set position, parts of platform and dash being shown in section to illustrate the electric connections. Fig. 2 is a plan view of the fender shown in Fig. 1. Fig. 3 is a view in front elevation of the tripping fender. Fig. 4 is a view in section on the line 4—4 of Fig. 1 with the netting removed for purposes of 40 clearness. Fig. 5 is a perspective view of the scoop member of the fender. Fig. 6 is a view in section on an enlarged scale on the line 6—6 of Fig. 3. Fig. 7 is a view in vertical longitudinal section through the 45 center of the fender, illustrating the latter in its position to pick up a person or object. Fig. 8 is a perspective view of the trip fender supporting shaft, and Fig. 9 is a dia- 50 grammatic rear elevation illustrating the

electric connections between the several 55 magnets.

1 represents a car and 2, 2, are brackets secured to the bottom 3 of the car and depending therefrom. These brackets 3 have upturned forward ends 4 supporting a shaft 5 extending transversely of the car and beyond the brackets 2. On this shaft 5, a scoop member 6 of my improved fender is pivotally mounted. Arms 31 are fixed to the shaft 5, secured to the scoop member 6 and project under the scoop member, acting as supports for the latter and for electro-magnets 28 hereinafter described.

The scoop member 6 constitutes a metal frame 7 connected by netting 8, and of a 70 length to project beyond the rails 9 of the track on which the car runs. Hangers 10 are secured to the bottom of the car and are positioned in advance of the brackets 2 to reinforce the bearings for the shaft 5, so 75 that the fender is rendered sufficiently strong to withstand the strains to which it is necessarily subjected.

Laterally swinging arms 11 are pivotally connected at their rear ends to the bottom 80 3 of the car, as shown at 12, and these arms are connected by a netting 13 with the scoop 6 and with the brackets 2 forming a netting inclosure. It is to be understood that this netting is sufficiently slack to allow the 85 scoop member to fall and also to allow the arms 11 to swing laterally, constituting a wide open mouth receptacle to receive a person or object.

At the forward end of the car, depending 90 brackets 14 are located and constitute bearings for a transverse shaft 15. A tripping fender 16 is secured to this shaft 15 and normally hangs in a vertical position, as clearly shown in Fig. 1, so that it will be 95 struck or engaged by a person or object on the track. This tripping fender may be made in various ways and I have illustrated it of the ordinary slat type.

The shaft 15 is provided with three upwardly projecting crank arms or pins 17, 18, and 19, respectively. The crank arms 17 and 19 are adjacent the ends of the shaft 15, and are connected by links 20 with upwardly projecting crank arms 21 fixedly secured on the shaft 5, so that the rearward and upward movement of the tripping fender 16 compels the scoop member 6 to move 100 105

downwardly. The crank arm 18 is located intermediate the ends of shaft 15, and is connected by a link 22 with a pair of toggle levers 23. These levers 23 at their outer ends are connected to the arms 11, so that when the link 22 is moved forwardly, the arms 11 will be swung laterally as will be readily understood.

As the tripping fender 16 is moved rearwardly and upwardly by contact with a person or object, it will be moved to the position shown most clearly in Fig. 7 and will engage a pivoted catch 24 projecting through a slot 25 in the car platform in a position 15 to be kicked by the operator to release the tripping fender whenever desired.

To prevent any possibility of the scoop member jumping up and down after it has been moved downwardly, I provide an arrangement of electro-magnets as will be now explained. Two of these magnets 26 are provided in the car platform and are adapted to attract metal blocks 27 on the tripping fender 16. Two electro-magnets 28 are provided on the forward end of the scoop member 6 in position to engage the rails 9, and these magnets are connected in an electric circuit including a source of supply 29 and a switch 30, as illustrated diagrammatically 30 in Fig. 9. This switch is, of course, to be located in convenient reach of the motor-man, and it is to be understood that the circuit to the magnets is maintained closed, so that as soon as the tripping fender is moved 35 rearwardly, and the metal blocks 27 approach the magnets 26, the power of the magnets 26 compels the completion of the movement of the tripping fender and the magnets 28 are attracted to the rails 9 and 40 securely hold the scoop member 6 in its lowered position.

When it is desired to re-set the fender, it is simply necessary to manually release the catch 29 and throw the switch 30 to open 45 the electric circuit, whereupon the tripping fender will fall to normal position, causing the scoop member 6 to be elevated to set position.

Various slight changes might be made in 50 the general form and arrangement of parts described without departing from my invention, and hence I do not limit myself to the precise details set forth, but consider myself at liberty to make such changes and 55 alterations as fairly fall within the spirit and scope of the appended claims.

Having thus described my invention, what I claim as new and desire to secure by Letters Patent is:

60 1. A fender comprising depending brackets, a scoop pivotally connected to the brackets, laterally swinging arms above the scoop, a flexible netting connecting the lateral arms with the scoop and the brackets, and means 65 for simultaneously swinging said arms lat-

erally and moving said scoop downwardly, substantially as described.

2. A fender comprising depending brackets, a scoop pivotally connected to the brackets, laterally swinging arms above the scoop, a flexible netting connecting the lateral arms with the scoop and the brackets, a tripping fender, and means connecting the tripping fender with said arms and with said scoop, whereby the movement of the tripping fender causes the arms to swing laterally and the scoop to move downwardly, substantially as described.

3. A fender comprising depending brackets, a scoop pivotally connected to the brackets, laterally swinging arms above the scoop, a flexible netting connecting the lateral arms with the scoop and the brackets, a tripping fender, a shaft constituting the pivot of the scoop, crank arms on the shaft, links connecting said crank arms with crank arms on the tripping fender, toggle levers connected to the arms, and a link connecting said toggle levers with a crank arm on the tripping fender, whereby the rearward movement of the tripping fender causes the lateral movement of the arms and the downward movement of the scoop, substantially as described.

4. A fender comprising depending brackets, a scoop pivotally connected to the brackets, laterally swinging arms above the scoop, a flexible netting connecting the lateral arms with the scoop and the brackets, means for simultaneously swinging said arms laterally and moving said scoop downwardly, and electro-magnets adapted to hold said parts with the arms in laterally extended position and the scoop in lowered position, substantially as described.

5. A fender comprising depending brackets, a scoop pivotally connected to the brackets, laterally swinging arms above the scoop, a flexible netting connecting the lateral arms with the scoop and the brackets, a tripping fender, means connecting the tripping fender with said arms and with said scoop, whereby the movement of the tripping fender causes the arms to swing laterally and the scoop to move downwardly, and electro-magnets adapted to hold said parts with the arms in laterally extended position and the scoop in lowered position, substantially as described.

6. A fender comprising depending brackets, a scoop pivotally connected to the brackets, laterally swinging arms above the scoop, a flexible netting connecting the lateral arms with the scoop and the brackets, a tripping fender, a shaft constituting the pivot of the scoop, crank arms on the shaft, links connecting said crank arms with crank arms on the tripping fender, toggle levers connected to the arms, a link connecting said toggle levers with a crank arm on the

tripping fender, whereby the rearward movement of the tripping fender causes the lateral movement of the arms and the downward movement of the scoop, and electro-magnets adapted to hold said parts with the arms in lateral extended position and the scoop in lowered position, substantially as described.

7. A fender comprising depending brackets, a scoop pivotally connected to the brackets, laterally swinging arms above the scoop, a flexible netting connecting the lateral arms with the scoop and the brackets, a tripping fender, means connecting the tripping fender with said arms and with said scoop, whereby the movement of the tripping fender causes the arms to swing laterally and the scoop to move downwardly, and a pivoted catch adapted to be engaged by and hold the tripping fender in its rearward position, substantially as described.

8. A fender comprising depending brackets, a scoop pivotally connected to the brackets, laterally swinging arms above the scoop, a flexible netting connecting the lateral arms with the scoop and the brackets, a tripping fender, a shaft constituting the pivot of the scoop, crank arms on the shaft, links connecting said crank arms with crank arms on the tripping fender, toggle levers connected to the arms, a link connecting said toggle levers with a crank arm on the tripping fender, whereby the rearward movement of the tripping fender causes the lateral movement of the arms and the downward movement of the scoop, and a pivoted catch adapted to be engaged by and hold the tripping fender in its rearward position, substantially as described.

40 9. A fender comprising brackets, a shaft supported in the brackets, a scoop secured to the shaft, crank arms secured to said shaft, laterally swinging pivoted arms, a flexible netting connecting said last-mentioned arms with the scoop and with the bracket forming a receptacle, toggle levers connecting the laterally swinging arms, a crank shaft supported in advance of the scoop, a tripping fender secured to said crank shaft, upwardly projecting crank arms on said last-mentioned shaft, links connecting certain of said last-mentioned crank arms with the first-mentioned crank arms, and a link connecting another of said last-mentioned crank arms with the toggle levers, whereby the rearward movement of the tripping fender compels the downward movement of the scoop and the lateral movement of said arms, substantially as described.

60 10. A fender comprising brackets, a shaft supported in the brackets, a scoop secured to the shaft, crank arms secured to said shaft, laterally swinging pivoted arms, a flexible netting connecting said last-mentioned arms with the scoop and with the bracket forming

a receptacle, toggle levers connecting the laterally swinging arms, a crank shaft supported in advance of the scoop, a tripping fender secured to said crank shaft, upwardly projecting crank arms on said last-mentioned shaft, links connecting certain of said last-mentioned crank arms with the first-mentioned crank arms, and a link connecting another of said last-mentioned crank arms with the toggle levers, whereby the rearward movement of the tripping fender compels the downward movement of the scoop and the lateral movement of said arms, and a pivoted catch adapted to be engaged by and hold the tripping fender in its rearward position, substantially as described.

70 11. A fender comprising brackets, a shaft supported in the brackets, a scoop secured to the shaft, crank arms secured to said shaft, laterally swinging pivoted arms, a flexible netting connecting said last-mentioned arms with the scoop and with the bracket forming a receptacle, toggle levers connecting the laterally swinging arms, a crank shaft supported in advance of the scoop, a tripping fender secured to said crank shaft, upwardly projecting crank arms on said last-mentioned shaft, links connecting certain of said last-mentioned crank arms with the first-mentioned crank arms, a link connecting another of said last-mentioned crank arms with the toggle levers, whereby the rearward movement of the tripping fender compels the downward movement of the scoop and the lateral movement of said arms, stationary electro-magnets adapted to attract metal pieces on the tripping fender and hold the latter in its rearward position, and electro-magnets on the scoop fender adapted to attract the rails and hold the scoop fender in lowered position, said electro-magnets being in circuit with a source of electricity supply and with a switch, and said circuit being normally closed, substantially as described.

75 12. A fender comprising brackets, a shaft supported in the brackets, a scoop secured to the shaft, crank arms secured to said shaft, laterally swinging pivoted arms, a flexible netting connecting said last-mentioned arms with the scoop and with the bracket forming a receptacle, toggle levers connecting the laterally swinging arms, a crank shaft supported in advance of the scoop, a tripping fender secured to said crank shaft, upwardly projecting crank arms on said last-mentioned shaft, links connecting certain of said last-mentioned crank arms with the first-mentioned crank arms, a link connecting another of said last-mentioned crank arms with the toggle levers, whereby the rearward movement of the tripping fender compels the downward movement of the scoop and the lateral movement of said arms, a pivoted

catch adapted to be engaged by and hold the tripping fender in its rearward position, stationary electro-magnets adapted to attract metal pieces on the tripping fender and hold the latter in its rearward position, and electro-magnets on the scoop fender adapted to attract the rails and hold the scoop fender in lowered position, said electro-magnets being in circuit with a source of 10 electricity supply and with a switch, and

said circuit being normally closed, substantially as described.

In testimony whereof I have signed my name to this specification in the presence of two subscribing witnesses.

DAVID CHEW.
